INVENTOR

BY Philip S. McLean
ATTY.

Justed and set for windows of different widths, and which will provide an awning construction which will include the window mounts, can all be quickly and easily put up and taken down within the window.

Further special objects are to provide automatic locking of the awning in place in the act of closing it, in supported position over the windows so that it will not be disturbed by the wind or the like, and to provide for easy unlocking of the awning from within the window when the awning is to be taken down.

Other objects of the invention are to provide an awning structure of simple, inexpensive construction which will have a minimum of appearance and which when taken down from over the window will not leave a multiplicity of supports or other articles to be stored.

Other desirable objects and the novel features throughout which the purposes of the invention are attained will appear in the following specification set forth in detail in the following specification.

The drawings accompanying and forming part of the specification illustrate the present practical embodiments of the invention. Strictly however, may be further modified and changes will within the spirit and the broad scope of the invention as hereinafter defined and claimed.

Fig. 1 is a side elevation of an awning embodying features of the invention; Fig. 2 is a broken front elevation of the upper portion of the same on a larger scale, with parts appearing in section;

Fig. 3 is a further enlarged broken detail of the waist rod and upper end portion of the awning;

Fig. 4 is a broken front sectional view illustrating the inclined form of longitudinally adjustable top rod for the awning;

Figs. 5 and 6 are combined views, broken and sectioned on different planes, illustrating top rail and supporting ring features;

Fig. 7 is a part sectional front elevation of the telescopically engageable tubular sections of the top rail;

Fig. 8 is an end elevation of one of the rail sections;

In Figs. 1 and 2, the body or fabric portion 10 of the awning is shown clamped and held

in place generally U-shaped with a rounded arch portion 12 and substantially straight sides 14, 15, the latter designed to receive the upper edge of the awning material between them and having means for securing them firmly together over such material.

In the illustration one side wall 16 of the rod has a transverse portion 17 through which are forced through the awning material and the longitudinal opening 18 provided in the other wall 14 and being drawn over the back of the latter as indicated in Figs. 5 and 6. This provides a simple, firm and secure means for fastening the supporting rods on the awning material.

20. The sliding telescopic engagement of the rod sections 11 and 12, which enables adjustment of the length of the rods to suit the width of the awning material and the extending portion of the awning material or awning through an opening or openings in the other section, serves to lock the sections together in their telescopic longitudinally adjustable relation, as particularly indicated in Fig. 2.

At their outer ends, the telescoscopically engaged rod sections 11 and 12 have outer reinforcement tabs, as indicated at 18, to reinforce the edge portions of the awning fabric, and these tabs may be woven fabric or the like, or a similar structure and effect to those already described.

35. The externally applied top rail described may be made of sheet metal or formed in the shape indicated, and this externally applied form of reinforcement eliminates need for hemming or other finishing of the upper edge of the awning material.

In cases where the awning material is stitched with a hem along its upper edge, the internal form of top rail illustrated in Fig. 4 may be employed, the same consisting of telescoscopically engaged sections 11 and 12 secured together in their longitudinally adjustable relation, as by rivets or other through fastenings 15a. These sections, when engaged and secured in their longitudinally adjustable relation, are inserted as a solid rod inside the stitched hem portion 19 along the upper edge of the awning material.

In both forms of the invention thus far described, the awning is supported by means of split rings having shank portions caught within

admitted as in Fig. 5.

Pulleys 26 may be provided for the cords 27 in place of the sliding pulleys having band portions 28, Fig. 4, perforated for passage of the shanks of the supporting rings.

Other forms of cord and pulleys may be used, construction indicated to be hung on the stems of the supporting rings.

The stay rods supporting the awning are indicated at 29, carried by base plates 30, secured over the top of the window frame, said base plates having catches 31, one of which is shown to close the hooks after the supporting rings 28 have been engaged therewith.

The stay rods are automatically locked in place by means of interconnected toggle levers in 32, 34, the first pivoted on the base at 35 and the second pivoted at 36 to a bell crank extension of the safety catch.

A stop such as indicated at 38 on one of the toggle levers, Fig. 3, prevents the toggle from "breaking" inwardly after the center pivot 39 or the toggle has been pushed outward just past the desired locking position.

To trip the toggles and allow the safety catches to open upwardly, fingers 40 are shown provided on the lower ends of the upper toggle levers 32, such finger extensions being located where they may be reached from inside the window.

20 U-shaped rod sections telescopically engaged over the outer end of the awning material, one side wall of each section having integral points extending through the awning material and the other side wall of each section having openings admitting said points and the latter being turned down over the second section to engage two adjacent sections in clamped engagement over the awning material, and one or more of said points on one section being turned down over the other section over which it is slidably engaged, to interlock the sections in their longitudinally added position.

JOSEPH EMILE COLEMAN.
